United States Patent [19]

Vitek

[11] Patent Number: Des. 313,586

[45] Date of Patent: ** Jan. 8, 1991

[54] INTEGRATED CIRCUIT CHIP CARRIER

[75] Inventor: Joseph I. Vitek, Baltimore, Md.

[73] Assignee: Westinghouse Electric Corp.,
Pittsburgh, Pa.

[**] Term: 14 Years

[21] Appl. No.: 934,373

[22] Filed: Nov. 24, 1986

[52] U.S. Cl. D13/182; D34/40

[57] CLAIM

The ornamental design for an integrated circuit chip carrier, as shown and described.

DESCRIPTION

FIG. 1 is a perspective view of an integrated circuit chip carrier showing my new design;

FIG. 2 is a top plan view thereof;

FIG. 3 is a bottom plan view thereof;

FIG. 4 is an end elevational view thereof; and

FIG. 5 is a side elevational view thereof, the opposite side elevational view being a mirror image.

FIG. 1

FIG. 2

FIG. 5

FIG. 4

FIG. 3
